UNITED STATES PATENT OFFICE.

HARRY A. DOUGLAS, OF BRONSON, MICHIGAN.

ELECTRIC SWITCH.

Application filed January 30, 1923. Serial No. 615,862.

To all whom it may concern:

Be it known that I, HARRY A. DOUGLAS, citizen of the United States, residing at Bronson, in the county of Branch and State 5 of Michigan, have invented a certain new and useful Improvement in Electric Switches, of which the following is a full, clear, concise, and exact description.

My invention relates to electric switches 10 and is of particular service in connection with those electric switches that are employed upon automobiles for the regulation of their ignition and lighting circuits, though the invention is not to be restricted to 15 any particular use to which it may be put.

The invention has for one of its objects the provision of an improved assembly between the casing of such a switch and the mounting plate therefor, this object of the invention 20 being realized by the provision of tongues upon one of these elements of the structure which projects through the other, these tongues being laterally deflected to maintain the casing and the mounting plate 25 in assembly.

The invention has for another of its objects an improved assemblage between the switch operating handle and the casing which encloses the switch parts. In carrying out this object of the invention the 30 switch handle is formed with a flange that is received in spacing that intervenes between the end wall of the casing and the mounting plate, the handle having a portion that projects through an opening in the casing into 35 engagement with the switch mechanism.

In accordance with another object of the invention, the switch has an actuating member which is formed with an opening in 40 which the portion of the handle that projects into the casing is received, this opening being of such shape as to prevent material relative turning movement of the handle and actuating member while permitting sliding 45 movement of the actuating member upon the handle. Spring means are provided within the casing for maintaining this actuating member in assembly with the handle, this spring means being preferably some of the 50 contacting mechanism of the switch.

The structure of my invention also employs one or more mounting nuts which are assembled with and between the switch casing and the mounting plate in a manner to 55 prevent the nuts from turning. The screws by which the switch is fastened in place are

suitably passed through the holes in these nuts.

In accordance with another characteristic of the invention a contact carrier is provided 60 at the end of the casing opposite the end wall thereof. There are also provided a contact actuator between the contact carrier and the casing end wall, a second contact carrier between the aforesaid contact carrier and the actuator, a contact upon the first contact carrier and accessible for engagement at the inner face of this contact carrier, and a contact upon the second contact carrier and positioned to be engageable with the contact 65 upon the first contact carrier, the contact upon the second contact carrier projecting into engagement with said contact actuator to enable the actuator to move the second contact carrier. In the preferred embodiment 70 of the invention the contact upon the second contact carrier is formed with a spring barrel exerting pressure at one end against the contact actuator and at its other end against the contact upon the second contact carrier whereby the contact actuator 75 may operate the second contact carrier without binding the action of the spring in said spring barrel. While this spring barrel is 80 preferably a part of the contact yet it performs a mechanical function and the invention is not therefore to be limited to the performance of this function by an element 85 which is also an electrical contact.

In accordance with another feature of the 90 invention the first contact carrier is provided with a pivotal formation upon which the second contact carrier is disposed and spring mechanism mechanically couples the contact actuator with the second contact carrier to 95 enable the second contact carrier to be turned by the actuator, this spring mechanism co-operating with the actuator to maintain the second contact carrier substantially in one plane of movement.

The invention in all of its details will be 100 more fully explained by reference to the accompanying drawings in which Fig. 1 is a view in elevation illustrating the preferred form of switch; Fig. 2 is a rear view of the switch; Figs. 3, 4 and 5 are sectional views respectively taken on lines 105 3-3, 4-4 and 5-5 of Fig. 6, the spring contacts upon the carriers revealed in Fig. 4 being removed; Fig. 6 is a sectional view 110 on line 6-6 of Fig. 3; Fig. 7 is a sectional view on line 7-7 of Fig. 9 illustrating the

manner in which a mounting nut is assembled with the casing and its mounting plate; Fig. 8 is a sectional view with a portion of the handle shown in elevation and 5 with some of the parts removed; Fig. 9 is a sectional view on line 9—9 of Fig. 3; Fig. 10 is a sectional view illustrating complementary contacts upon two contact carriers; and Fig. 11 is a perspective view of a 10 portion of the handle looking from the inside thereof.

Like parts are indicated by similar characters of reference throughout the different figures.

15 The casing has an end wall 1 and a side wall 2, the wall 1 being essentially flat and the wall 2 being preferably cylindrical. A mounting plate 3 is disposed over the end wall and upon the exterior of the casing 20 beyond which the mounting plate laterally projects. One of these elements, preferably the mounting plate, is formed with a plurality of tongues 4 which project through openings formed in the end wall 25 1 of the casing. These tongues are laterally deflected as indicated at 5 so that the end wall is interposed and clamped between the laterally deflected ends of the tongues and the body portions of the mounting plate. 30 The mounting plate is desirably circular and co-axial with the casing and it has a central circular raised portion 6 which is concentric with the mounting plate and the casing and through which a large circular opening 7 35 is formed, this opening being likewise co-axial with the casing and plate. One or more arcuate slots 8, also concentric with the casing, are formed through the end wall thereof and are aligned with the opening 7, these slots being formed in depressed portions 9. The end wall of the casing and the raised portion 6 of this mounting plate are spaced apart to receive arcuate flanges 40 10 formed upon one end of the handle 11, the flanges, the end wall of the casing, and the casing mounting plate co-operating to define a plane of rotation or oscillation for the handle. The switching mechanism includes an actuating member 12 here shown 45 as being in the form of a ring. This ring is formed with wide notches 13 upon its inner circular face. These notches receive the handle portions 14 which project into the interior of the casing through the arcuate slots 8. Said notches or openings are 50 55 of such shape as to prevent material relative turning movement between the handle and actuating member while desirably permitting sliding movement of the actuating member upon the handle.

60 A contact carrier 15 carries bayonet pins 16 that are receivable in bayonet slots 17 formed in the cylindrical wall of the casing. This contact carrier carries contacts 18, 19, 20, etc., which pertain to the different

circuits, the circuit relation thereof being immaterial so far as my invention is concerned. These contacts are shown in the form of threaded rods which are screwed into holes that are formed through the contact carrier and are provided with suitable binding screws upon the outer ends as indicated at 21. The inner ends of the rods 18 are slightly dished so as to receive contacts that are provided upon one or more contact carriers that are supplied in addition to the contact carrier 15. Another contact carrier 22 is interposed between the contact carrier 15 and the contact actuator 12, the contact carrier 22 being desirably 70 in the form of a metallic ring which is co-axial with the actuating member 12 and the switch casing. The ring 22 carries a series of metallic contacts 23 which are formed with spring barrels 24 that have clinching 80 formations 25 Fig. 10 upon one side of the ring to hold this ring in firm assembly with the contacts 23 upon the other side of this ring. The spring barrels 24 slide within openings formed transversely in the 85 actuating ring 12 whereby this actuating ring engages sides of these barrels to force the barrels to turn therewith whereby the ring 12, in being turned, will turn the ring 22 to shift the contacts 23 into and out of 90 engagement with the complementary contacts upon the carrier 15. This carrier is formed with depressions, clearly illustrated in Fig. 6, which receive the contacts 23 when the switch is in open circuit position, the carrier 15 being formed of insulating material. 95

The contacts 23 are pressed toward the carrier 15 and the actuating ring 12 is pressed against the depressed portions 9 of the end wall of the casing by means of coiled springs 26 that are located within the spring barrels 24, these coiled springs pressing each at one end upon the contacts 23 and each at its other end against the actuating ring 12. The springs 26 desirably exert their pressure upon the latter ring through the intermediation of plungers or buttons 27 that extend into the barrels or project therefrom for the purpose. By the assembly illustrated the contact actuating ring 12 may perform its function without binding the springs 26. 105 110 115

While the spring barrels and contacts 23 are desirably parts of integral structures the invention is not to be thus limited, it being 120 obvious that the mechanical function performed by the spring barrel and the springs therein may be accomplished whether the spring barrels are integrally formed with the contacts 23 or not.

There is a central sleeve 28 that is co-axial with the handle and with the casing and other rotating parts of the switch. The sleeve is assembled with the casing by means of tongues 28' formed upon the sleeve and 130

clinched with the end wall of the casing, Fig. 6. This sleeve houses the barrel 29 of any suitable lock which is accessible from the front of the handle. The sleeve is shown 5 with slots 30 into which the tumblers 31 of the lock may be projected when operated by a key in order to lock the inner contact carrier 34 and from which the tumblers may be withdrawn when the contact carrier 34 is to 10 be unlocked and readjusted, the handle controlled switch being preferably always adjustable.

The rotating part of the lock carries a 15 projection 32 which extends into the switch casing through a central opening in the end wall of the casing. A contact actuator 33 is formed with an opening that receives the projection 32, this opening being of such 20 shape as to prevent material relative turning movement between the actuator 33 and the projection 32 but permitting sliding movement of this actuator 33 upon the lock projection 32. The contact carrier 34 is 25 interposed between the contact carrier 15 and the contact actuator 33. This contact carrier 34 is shown as being in the form of a triangular plate. It has a central depression 35 which is received upon the inner end of the central contact 19 in the contact carrier 30 15, these portions 35 and 19 constituting complementary contacts as the switch is illustrated. The contact carrying plate 34 is thus obviously mounted to be turned to the extent defined by the turning movement of 35 the lock projection 32 through the intermed- diation of parts now to be described.

The contact carrier 34 carries spring de- 40 vices assembled therewith as the spring de- vice illustrated in Fig. 10 is assembled with the contact carrier 22. The parts of the 45 spring devices which assemble the contact carrier 34 with the contact actuator 33 are similar to the parts shown in Fig. 10 and are given similar characters of reference with prime exponents added. As the invention 50 is illustrated there are three of these spring devices which are distributed around the axis of turning movement of the contact carrier 34. Contacts 12 and 13, as illus- 55 trated in Fig. 4, are shown with the contacts removed therefrom. These spring de- vices serve to maintain the contact actuator 33 in engagement with the lock projection 32 and also serve to maintain the contact carrier 34 in its plane of movement. As il- 60 lustrated the spring barrel of one of the spring devices pertaining to the contact carrier 34 has added thereto a contact 37 to en- gage one or more complementary contacts upon the carrier 15. A switch thus 65 constructed may be fastened in place with the aid of nuts 38 formed with threaded holes therethrough. These nuts are polygonal in contour and have their sides in engagement with the projecting edge portions 39 that

project laterally of the mounting plate to prevent the nuts from turning. These nuts are located upon the inner sides of the mounting plates and project into openings 40 that are formed in the side wall of the 70 casing and extend over into the end wall, these openings preventing movement of the nuts lengthwise of the switch. The openings 40 are desirably extended as indicated at 41 to receive portions of screws passed 75 through the nuts.

While I have herein shown and partic- 80 ularly described the preferred embodiment of my invention I do not wish to be limited to the precise details of construction shown as changes may readily be made without de- parting from the spirit of my invention, but having thus described my invention I claim as new and desire to secure by Letters Patent the following:

1. A switch structure including a casing 85 having an end wall; a plate disposed at the end wall and upon the exterior of the cas- ing, there being aligned openings in the plate and end wall and a space between the plate and end wall; switching mechanism 90 within the casing; and a switch handle having an accessible portion upon the exterior of the casing and another portion pro- jecting into the casing and there assembled with the switching mechanism to enable the handle to operate such mechanism, said handle having a flange which is received in the space between the end wall and plate.

2. A switch structure including a casing 100 having an end wall; a plate disposed at the end wall and upon the exterior of the cas- ing, there being aligned openings in the plate and end wall and a space between the plate and end wall; switching mechanism 105 within the casing; and a switch handle mounted to turn upon the casing and hav- ing an accessible portion upon the exterior of the casing and another portion project- ing into the casing and there assembled with 110 the switching mechanism to enable the han- dle to operate such mechanism, said handle having a flange which is received in the space between the end wall and the plate, the switching mechanism having an actuating 115 member formed with an opening in which the portion of the handle that projects into the casing is received, this opening being of such shape as to prevent material relative turning movement of the handle and actuating member while permitting sliding movement of the actuating member upon the handle.

3. A switch structure including a casing 125 having an end wall; a plate disposed at the end wall and upon the exterior of the cas- ing, there being aligned openings in the plate and end wall and a space between the plate and end wall; switching mechanism within the casing; a switch handle mounted 130

- to turn upon the casing and having an accessible portion upon the exterior of the casing and another portion projecting into the casing and there assembled with the 5 switching mechanism to enable the handle to operate such mechanism, said handle having a flange which is received in the space between the end wall and the plate, the switching mechanism having an actuating 10 member formed with an opening in which the portion of the handle that projects into the casing is received, this opening being of such shape as to prevent material relative turning movement of the handle and actuating 15 member while permitting sliding movement of the actuating member upon the handle; and spring mechanism pressing the actuating member toward the end wall of the casing.
- 20 4. A switch structure including a casing having an end wall; a plate disposed at the end wall and upon the exterior of the casing, there being aligned openings in the plate and end wall; switching mechanism 25 within the casing; a switch handle mounted to turn upon the casing and having an accessible portion upon the exterior of the casing and another portion projecting into the casing and there assembled with the switching 30 mechanism to enable the handle to operate such mechanism, the switching mechanism having an actuating member formed with an opening in which the portion of the handle that projects into the casing is received, this opening being of such shape as to prevent material relative turning movement of the handle and actuating member while permitting sliding movement of the actuating member upon the handle; and 35 spring mechanism pressing the actuating member toward the end wall of the casing.
- 40 5. A switch structure including a casing having end and side walls; a mounting plate disposed at the end wall and upon the exterior of the casing beyond which the mounting plate laterally projects and which mounting plate has an edge portion projecting rearwardly therefrom, the mounting plate having an opening aligned with the side wall of the casing and the side wall of the casing having an opening aligned with the aforesaid opening, this opening in the casing side wall being continued inwardly into the end wall of the casing; and a nut 45 of polygonal contour engaging the aforesaid laterally projecting edge portion of the mounting plate and also engaging marginal portions of the opening in the casing, the portion of the latter opening that is in the side wall of the casing being continued sufficiently away from the end wall of the casing to receive the projecting end of a screw or bolt passed through said nut.
- 50 6. A switch structure including a casing having end and side walls; a mounting plate

disposed at the end wall and upon the exterior of the casing beyond which the mounting plate laterally projects and which mounting plate has an edge portion projecting rearwardly therefrom, the mounting plate having an opening aligned with the side wall of the casing and the side wall of the casing having an opening aligned with the aforesaid opening, this opening in the casing side wall being continued inwardly 70 into the end wall of the casing; and a nut of polygonal contour engaging the aforesaid laterally projecting edge portion of the mounting plate and also engaging marginal portions of the opening in the casing. 75

7. An electric switch including a casing having a wall at one end of the casing; a contact carrier at the other end of the casing; a contact actuator between the contact carrier and the casing end wall; a second contact carrier between the aforesaid contact carrier and the actuator; a contact upon the first contact carrier and accessible for engagement at the inner face of this contact carrier; and a contact upon the second contact carrier and positioned to be engageable with the contact upon the first contact carrier, the contact upon the second contact carrier being formed with a spring barrel that projects toward the contact actuator and which actuator engages the side of the barrel to move the second contact carrier through the intermediation of the barrel, there being a spring in this barrel exerting pressure at one end against the contact actuator and at its other end against the contact upon the second contact carrier whereby the contact actuator may operate the second contact carrier without binding the action of the spring in said spring barrel. 100

8. An electric switch including a casing having a wall at one end of the casing; a contact carrier at the other end of the casing; a contact actuator between the contact carrier and the casing end wall; a second contact carrier between the aforesaid contact carrier and the actuator; a contact upon the first contact carrier and accessible for engagement at the inner face of this contact carrier; a contact upon the second contact carrier and positioned to be engageable with the contact upon the first contact carrier; and a spring barrel upon the second contact carrier and projecting toward the contact actuator that engages the side of the barrel to move the second contact carrier through the intermediation of the barrel without binding the spring in the barrel. 110

9. An electric switch including a casing having a wall at one end of the casing; a contact carrier at the other end of the casing; a contact actuator between the contact carrier and the casing end wall, this contact actuator being mounted to turn in a plane 125

- substantially parallel with the plane of the aforesaid contact carrier; a second contact carrier between the aforesaid contact carrier and the actuator; a contact upon the 5 first contact carrier and accessible for engagement at the inner face of this contact carrier; and a contact upon the second contact carrier and positioned to be engageable with the contact upon the first contact carrier, the contact upon the second contact carrier being formed with a spring barrel that projects toward the contact actuator and which actuator engages the side of the barrel to turn the second contact carrier 10 through the intermediation of the barrel, there being a spring in this barrel exerting pressure at one end against the contact actuator and at its other end against the contact upon the second contact carrier where- 15 by the contact actuator may operate the second contact carrier without binding the action of the spring in said spring barrel.
10. An electric switch including a casing having a wall at one end of the casing; a 20 contact carrier at the other end of the casing; a contact actuator between the contact carrier and the casing end wall, this contact actuator being mounted to turn in a plane substantially parallel with the plane of the 25 aforesaid contact carrier and the actuator; a contact upon the first contact carrier and accessible for engagement at the inner face of this contact carrier; a contact upon the second contact carrier and positioned to be 30 engageable with the contact upon the first contact carrier; and a spring barrel upon 35 the second contact carrier and projecting toward the contact actuator that engages the side of the barrel to turn the second contact carrier through the intermediation of the barrel without binding the spring in the barrel.
11. An electric switch including a contact carrier; a second contact carrier pivoted upon the first; complemental contacts upon 40 the contact carriers; an actuator for the second contact carrier; and leveling springs upon different sides of the axis of the second contact carrier and interposed between this second contact carrier and the contact 45 actuator and engaging the contact actuator to enable the contact actuator to turn the second contact carrier and co-operating with the contact actuator to maintain the second contact carrier substantially in one 50 plane of movement.
12. An electric switch including a contact carrier; a second contact carrier pivoted upon the first; complemental contacts upon 55 the contact carriers; an actuator for the second contact carrier; and spring mechanism mechanically coupling the contact actuator with the second contact carrier to enable the second contact carrier to be turned by the actuator and co-operating with the 60 actuator to maintain the second contact carrier substantially in one plane of movement.

In witness whereof, I hereunto subscribe my name this 25th day of January A. D., 70 1923.

HARRY A. DOUGLAS.
